DESIGN FOR A FLATIRON

Albert Maescher, St. Louis, Mo., assignor to Crown Manufacturing Co., St. Louis, Mo., a corporation of Missouri

Application October 2, 1940, Serial No. 95,574

Term of patent 14 years

To all whom it may concern:

Be it known that I, Albert Maescher, a citizen of the United States and a resident of the city of St. Louis and State of Missouri, have invented a new, original, and ornamental Design for Flatiron, of which the following is a specification, reference being had to the accompanying drawing, forming part thereof.

Fig. 1 is a side elevational view of a flatiron embodying my new design;

Fig. 2 is a rear elevational view thereof;
Fig. 3 is a top plan view thereof; and
Fig. 4 is an end elevational view thereof.
The dominant features of my design reside in the portions shown in full lines.

I claim:

The ornamental design for a flatiron, as shown and described.

ALBERT MAESCHER.
